(57) **CLAIM**

I claim the ornamental design for a newtype outdoor anti-mosquito net with LED lights, as shown and described.

DESCRIPTION

FIG. 1 is a front perspective view of a newtype outdoor anti-mosquito net with LED lights showing my ornamental design;

FIG. 2 is a rear and bottom perspective view of a newtype outdoor anti-mosquito net with LED lights showing my ornamental design;

FIG. 3 is a front view of a newtype outdoor anti-mosquito net with LED lights showing my ornamental design;

FIG. 4 is a rear view of a newtype outdoor anti-mosquito net with LED lights showing my ornamental design;

FIG. 5 is a left side view of a newtype outdoor anti-mosquito net with LED lights showing my ornamental design;

FIG. 6 is a right side view of a newtype outdoor anti-mosquito net with LED lights showing my ornamental design;

FIG. 7 is a top view of a newtype outdoor anti-mosquito net with LED lights showing my ornamental design;

FIG. 8 is a bottom view of a newtype outdoor anti-mosquito net with LED lights showing my ornamental design; and,

FIG. 9 is an enlarged view of the area of FIG. 1 that is labeled with reference number 9.

The broken line showing of portions of the design is included for the purpose of illustrating only and forms no part of the claimed design.
